UNITED STATES PATENT OFFICE.

HUGH W. HUNTER, OF DANBURY, CONNECTICUT.

HAT-BLOCKING MACHINE.

Application filed November 16, 1926. Serial No. 148,747.

This invention relates to hat blocking machines, and it has particular relation to blocking machines of the type by which a hat body is placed upon a hat block and the crown and brim thereof are blocked as a preliminary to the finishing of the hat body.

In the finishing of hats, it is necessary to mount the hat body, which has been roughly blocked and pounced, upon a block of the contour and size of the completed hat. Heretofore, it has been customary to shape the crown of the hat body over the block and to pull out the brim of the hat by hand. This practice requires numerous steps, such as the pulling of the crown over the block, subjecting the felt to a steaming action, pulling down the base of the crown with a "puller down", smoothing the wringles from the crown, "cording" the base of the crown to the block, and finally pulling out the brim. Due to the rough block of the hat as it comes to the finisher, it requires no little effort to pull the hat crown over the block, and stretching or pulling of the brim by hand presents greater difficulties, especially when the hat brims are of narrow width. In addition to the time required by the various steps above outlined and the effort expended, the felt texture of the hat body and particularly of the brim is subjected to uneven strains by virtue of the inability to simultaneously pull out the whole area of the brim by hand.

It is, therefore, one of the principal objects of this invention to provide a blocking machine which positions a hat body upon a block and which shapes and stretches the brim as a preliminary step in the finishing operation on the hat. A further object is the provision of a blocking machine which acts to positively block a hat body and which distributes the blocking strains uniformly throughout the area of the hat body. A further object is the provision of a blocking machine of the above character which is operated by a system of hand levers to positively block a hat body to desired shape. A further object is to provide a machine to uniformly and simultaneously pull out and stretch the brim of a hat body throughout the brim area. A further object is the provision of a machine which pulls a hat body, previously

rough-blocked, over a block as a preliminary to the finishing of the hat body, and pulls out the brim thereof, whereby to materially decrease the time expended in accomplishing the same result by hand. A further object is to provide a machine which mounts a hat body on the block upon which the hat is finished. A further object is the provision of an improved method of "dry" blocking a hat body as a step preliminary to the finishing of the hat body. A further object is the provision of a machine of the above described character which is simple yet positive in operation and which efficiently attains the objects above set forth.

Other objects will be in part obvious and in part hereinafter pointed out in connection with the following analysis of the present invention wherein is shown one of the various possible embodiments of the invention, and in which drawing—

Fig. 1 is a front elevation, partly in section, of the entire blocking machine.

Fig. 2 is a side elevation of the machine as shown in Fig. 1, certain parts being broken away.

Fig. 3 is a top plan view of the blocking machine, certain of the operating levers being broken away.

Fig. 4 is a detail sectional view showing the relation of the various parts upon the completion of the blocking operation.

Fig. 5 is a detail of the brim clamps during various stages of their actuation.

Fig. 6 is a detail of the lever indicator.

Fig. 7 is a rear elevation of the brim clamps shown in detail in Fig. 5.

Referring to the drawings, numerals 10 and 11 designate side frames cast to form bases 12, uprights 13, lower cross pieces 14 and upper cross pieces 15, as will be readily understood. Front and rear tie rods 16 having reduced end portions 17 pass thru bosses 18 formed on side frames 10 and 11, and are securely bolted thereto by bolts 20, to both space and support the side frames in their desired upright relation. A cross plate or saddle member 21 secured to the upper cross pieces 15 of the side frames extends therebetween for the purpose described hereinafter. There is provided a top plate or table 22, comprising

a casting having a central open portion of substantially elliptical shape, which joins and is rigidly secured to the side frames 10 and 11 as by bolts 23. It will be understood that the conventional shape of the frame work as above described may be varied as desired.

Mounted on the cross saddle 21 intermediate the side frames 10 and 11, and secured thereto as by bolts 24 is a steam pot 25 preferably elliptical in shape, and which extends thru the opening in the table 22. Steam is admitted to the pot from any desired source thru pipe 26 and steam admission is controlled by a valve 27. The steam pot is open at its upper end and has on its bottom surface a channeled depression 28, to permit the condensate to be drained off and removed thru a drainage pipe 30.

A holding ring 31 preferably of brass and of oval or elliptical shape is mounted above the steam pot 25 by straps 32 pinned or riveted thereto as at 33, and bolted or otherwise secured to the steam pot as designated at 34. The brass ring 31 is machined on its inner and top surfaces to provide a bearing surface for one of a series of bands 35, likewise of brass, each of which is detachably mounted on the ring 31. The rings 35 are oval to conform to the oval shape of a hat block, and the particular band to be mounted is selected in accordance with the crown size of the hat to be blocked. The inner surface of the band 35 defines the junction of the crown and brim of the hat body when blocked. The bands 35 have an outside machined depression indicated at 36 of uniform diameter and depth, and thus any band selected will snugly fit on the ring 31.

To grip the edge of the brim of the hat body, which, as will be hereinafter explained, is supported from the band 35, I provide a plurality of brim clamps mounted from the table plate 22 and adapted to be brought into gripping relation by a hand lever. With reference to Figs. 4 and 5, each of the brim clamps comprise a lower jaw 40 having a brim engaging surface 41, and a finger 42 reciprocably mounted in the jaw member and having a gripping surface 43 complementary to the surface 41. A rearwardly extending portion of the lower jaw member is cast to form a slot or is otherwise bifurcated to accommodate the finger 42. By means of a pin 44, the jaw member 40 is pivotally mounted from a plate support 45 which is bolted to and overhangs the table 22, and the jaw members may swing about their fulcrums and are permitted an arcuate travel with respect to the plate support 45 and the table 22. The finger 42 extends inwardly of the table 22 and substantially below the level thereof and is operatively joined to the bifurcated head 46 of the stud bolt 47 by means of a pin 48. The stud bolt 47 extends thru a cast ring 50 of substantially oval or elliptical shape

which is positioned about the steam pot 25 and has a downwardly extending flange 51. A nut 52 is threaded to the end of the bolt 47 and is spaced from the under side of the cast ring 50 by a bushing 53 of rubber or other elastic material and by a washer 54. Considering that the finger 42 is in gripping relation with the jaw member 40 as shown in full lines, Fig. 5, it will be seen that an upward movement of the cast ring 50 will cause the finger 42 to be raised into non-gripping relation as indicated by dotted lines and that a subsequent downward operation of the cast ring 50 will bring the finger 42 into gripping relation with the lower jaw 40. The pivotal mounting of the finger 42 in the stud bolt 47 permits the finger 42 to travel outwardly or in clockwise direction (Fig. 5) with the jaw member 40 when the latter is so actuated, while the rubber bushing serves to permit an elastic gripping of the bearing surfaces 43 and 41 of the finger 42 and the jaw member 40 respectively to reduce to a minimum any marking of the hat held therebetween. It will be understood that a predetermined number of fingers similar to fingers 42 are arranged in spaced relation with respect to the table 22 and are joined to cast ring 50, the fingers being positioned to conform to the oval of the hat brim, and that all of the fingers are simultaneously and uniformly actuated upon movement imparted to cast ring 50.

The lower gripping jaw 40 has an inwardly directed portion 55, the under part of which forms a cam surface 56 angularly disposed to the vertical. Closely adjacent the cam surface 56 and disposed relatively inwardly thereof and in operative relation thereto, I provide an expansion ring 57 which may be rectangular in cross section, as shown, or of other cross section, and of an oval or elliptical configuration to conform to the shape of a hat block. The jaw member 40 has a sidewardly extending projection or extension 58 having therein an elongated slot 60. A screw or pin 61 or other form of connection passes loosely thru slot 60 and is threaded in the expansion ring 57. A tongue 62 extends from the cam surface 56 of jaw member 40 and engages in a groove 63 provided in ring 57. Referring to Figs. 1 and 5, it will be seen that as expansion ring 57 is projected upwardly, it engages the cam surface 56 of the jaw member 40 and expands the same by swinging it outwardly in a clockwise direction about its pivot pin 44. A plurality of jaws 40 are positioned at spaced intervals about the ring 57 to conform to the oval shape of the periphery of the hat brim. The tongues 62 operating in guide grooves 63 serve to maintain the jaws 40 in their predetermined spaced relation at all times. Upon downward operation of the expansion ring 57, the screws or pins 61 operating in slots 60 of the jaw extensions 58 cause the jaws to be

retracted. The slots 60 are, therefore, designed to be sufficiently long to accommodate for the maximum travel of the jaw members 40.

5 As shown in Fig. 3, I have provided twenty-four of the grippings units, as above described, spaced radially of the geometric center of the hat brim and about the periphery of the brim at equal arcuate distances 10 from each other to conform to the oval or elliptical outline thereof. It is to be understood that the number of such gripping units is arbitrary, and I do not wish to be limited by such a set number, which may be altered 15 as conditions require.

Considering now the mechanism by which the cast ring 50 may be raised or lowered to bring the fingers 42 into gripping and non-gripping relation with jaws 40, 65 is a lever 20 having at one end a handle portion 66 and at the other end a housing 67, mounted on eccentric plate 68 at the front upper part (the operator's left side) of the side frame 10 by means of a pin 69. Stops 70 are provided 25 to limit the arcuate travel of the lever 65 and the handle 66. Depending from the eccentric plate is a rod 71 threaded into a bifurcated clevis 72. A lock nut 73 is provided to adjust the operative length of rod 71. 30 74 is a cross arm which is pivotally joined to the bifurcated ends of the clevis 72 by a pin 75, and at its other end is keyed or otherwise secured to a rock shaft 76. The shaft 76 extends between frames 10 and 11, and is 35 journaled in bosses 77 and held from endwise movement by collars 78. Adjacent each side frame 10 and 11 at the inside thereof, I provide collars 80, rigidly secured to the rock shaft 76 as by set screws 81, the collars having eccentric arms 82 cast integrally therewith and at the end of the arms 82, pins 83 extend thru slots 84 in bars 85. The bars 85 extend in upright position and are journaled 40 in guide brackets 86 secured to the side frames 10 and 11 at their lower cross portions. Pins 87 screw-threaded to the bars 85 extend thru elongated slots 88 in the guide brackets 86. The bars 85 extend upwardly thru apertures 90 in the cross saddle 21, and are rigidly secured at their top ends as by bolts 91 to the 45 downwardly extending flange 51 of cast ring 50. The bars 85 are joined to the cast ring 50 at each side thereof so that a positive raising and lowering action may be imparted thereto. 50 From the above, it will be seen that the clockwise rotation (Fig. 2) of lever 65 and handle 66 has resulted in shaft 76 being rocked, causing the bars 85 to be lowered, thus lowering the cast ring 50 and bringing the fingers 60 42 into gripping relation with the jaws 40 as shown. The stop lug 70 on housing 67 is arranged to engage the base of eccentric plate 68 upon full actuation of lever 65 into the position shown in Fig. 2, and eccentric plate 68 is carried past its center and is thus

locked to hold fingers 42 in gripping relation.

Considering now the mechanism by which the jaws 40 and the fingers 42 are expanded radially to stretch a hat brim gripped therebetween, there is provided a hand lever 95 adjacent the side frame 11 (the operator's right side) which has a downwardly extending portion merging into a boss or collar 96, the later being keyed or otherwise secured to 70 a shaft 97. The shaft 97 is rotatably journaled in bosses 98, cast in side frames 10 and 11, and restrained from endwise movement by a collar 100 fixed thereto. Carried by the shaft 97 are collars 101 fixed thereto as by 75 set screws 102, each of the collars having a cast arcuate extension to provide a segment gear 103. The positioning of collars 101 and segment gears 103 carried thereby on the shaft 97 is such that the teeth of the segment 80 gears engage and mesh with teeth 104 at the lower end of rack bars 105. 106 designates upstanding bosses cast on the saddle member 85 ber 21 and arranged sidewardly of the steam pot 25 and along the line of the transverse center thereof. Boss extensions 107 are provided and secured to bosses 106 as by bolts 108. The rack bars 105 extend thru bores in the bosses 106 and extension bosses 107 wherein they are suitable journaled and supported, 90 and at their upper portions have reduced ends 110 which are screw-threaded into the expansion ring 57. Connection between the expansion ring 57 and the rack bars 105 is thus 95 made at each side of ring 57 to furnish a uniform raising effort. It will be seen from the above that by bringing the lever 95 forwardly (Fig. 1) the shaft 97 is rocked, and the segment gears 103 engage the rack bars 105 and cause the same to be projected upwardly and to similarly raise the expansion ring 57. This upward actuation of expansion ring 57 causes the jaws 40 to swing about their fulcrums 44 thereby moving into expanded position indicated by dotted lines, 100 105 Fig. 5.

To hold the jaw in this expanded position, a segmental ratchet 111 is bolted as at 112 or otherwise secured to the side frame 11 adjacent the lever 95. A pawl 113 is pivotally secured to lever 95 by pin 114 to engage the teeth of the ratchet 111 and is dropped into or removed from operative engagement with the teeth of the ratchet by an arm 114^a. This arm is joined to the pawl 113 by a cotter pin 115 and extends upwardly along the hand lever 95 where it is eccentrically connected as at 116 to a pawl operating handle 117 pivotally secured to lever 95. The operator may rock the handle 117 to raise the pawl 113 during 120 the swinging of hand lever 95 forwardly. When the jaws 40 have been sufficiently expanded, the pawl handle is released and the pawl 113 drops by gravity into a tooth of ratchet 111 to hold the jaws so expanded. I 125 130

propose to graduate the teeth of ratchet 111 in such a manner that their progression is in accordance with the various sizes of hat brims desired; that is, one tooth represents the travel of lever 95 for a three-inch brim, the next tooth represents a like operation for a three-and-a-half inch brim, and so on. A graduated plate 118 secured to ratchet 111 (Fig. 6) is inscribed with numbers, such as 5 10 15 20 25 30 35 40 45 50 55 60 65 70 75 80 85 90 95 100 105 110 115 120 125 130 135 140 145 150 155 160 165 To provide against the tendency of the felt to give and then to return partly to its original texture, the presser block 132 is designed to force the block 136 a slight excess distance 5 into the hat crown. It is evident that the hat body is now blocked on the block 134 as desired and its brim substantially stretched. To remove the hat and hat block from the machine, the lever 128 carrying the presser 10 block 132 is released and is raised by virtue of weight 125. The operator then releases the lever 65 and moves it rearwardly, and the disengagement of the fingers 42 from the jaws 40 is thereby effected, as well as the automatic cutting off of steam admission to the 15 steam pot 25. The operator then grasps the hat block by its chuck portion and raises the same with the blocked hat body thereon from ring 35; the hat body is now suitably blocked 20 and is positioned on the correct block ready for the finishing operation. Lever 95 is then released and swung rearwardly to retract the brim clamps for subsequent blocking.

In some instances, as where the rough 25 blocking operation has produced a crudely blocked hat, wrinkles may form along the upper side portions or the zone generally known as the square of the crown when a hat block is forced therein as above described. To ob- 30 viate this difficulty, I provide friction elements 137 secured to the sides of steam pot 25 to frictionally engage that portion of the crown so affected. The friction elements comprise elastic pads 138 of rubber or the 35 like, mounted on studs 139 which in turn are slidably mounted in straps 140 secured to the steam pot as by bolts 141. Pins 142 at the ends of studs 139 prevent the withdrawal thereof from straps 140. Springs 143 surround the studs 139 and urge the pads 138 40 into extended position. As the hat block 136 is forced downwardly by presser block 132, the side tip surface of the hat crown engages the elastic pads which by reason of their 45 resilient and frictional engagement there-with smooth out wrinkles which might occur.

In some instances, I propose to make the 50 ring 31 carrying band 35 vertically movable to provide greater ease in positioning the hat body so that its brim might be gripped between fingers 42 and jaws 40. In such a case, the ring 31 would be in lowered position at the beginning of the hat blocking operation, but would be raised in the position as 55 shown by actuation of lever 95 thru a connection with bars 105 or with expansion ring 57.

It will be evident that by the above de- 60 scribed blocking machine and by the art practiced in the use of the same, a rough blocked hat ready for the finishing operation may be quickly and expeditiously placed on the proper block upon which it is to be finished and the brim of the hat stretched without the many difficulties attendant to the

accomplishment of the same result by hand. The stretching of the brim is attained in a more uniform and positive manner than by a like hand operation and without the labor and time involved with the latter. The ma- 70 chine is simple in operation, has relatively few parts, all of which are easily accessible, and all moving parts thereof are positively actuated and suitably designed for a greater efficiency in the particular art. 75

Altho the above invention has been de- 80 scribed with relation to the art of "dry" blocking hats, that is, where only steam is used to soften the felt fibers as a preliminary to the finishing of the hat, the blocking ma- 85 chine as above described and the principles involved are applicable, without material modification, to the art of "wet" blocking hats, that is, the softening of the felt fibers by boiling water and steam in the rough blocking of hats of cone-shaped body and/or of stretched body, and such is comprehended within the scope of my invention.

From the above, it will be seen that the 90 present invention contemplates a practical device well adapted to accomplish, among others, all of the objects and advantages herein set forth.

I claim:

1. In a hat blocking machine, the combination of a plurality of brim clamps to grip the edge of a hat brim therebetween, means engaging the brim clamps to swing the clamps outwardly whereby to stretch the hat brim, and means on said brim clamps engaging said first named means to guide the brim clamps as they are swung outwardly. 95

2. In a hat blocking machine, the combination of a plurality of brim clamps, an expansion ring adapted to swing the brim clamps outwardly, and means on said brim clamps engaging in said expansion ring to guide the brim clamps as they are swung outwardly. 105

3. In a hat blocking machine, the combination of a plurality of pivotally mounted brim clamps comprising complementary gripping members, cam surfaces disposed on one of said complementary members between the fulcums and gripping portions thereof, and means engaging said cam surfaces to swing the brim clamps outwardly. 110

4. In a hat blocking machine, the combination of a plurality of pivotally mounted brim clamps comprising complementary gripping members, one of said complementary members having cam surfaces disposed between the fulcums and the gripping portions thereof, and an expansion ring engaging said cam surfaces to swing the brim clamps outwardly. 120

5. In a hat blocking machine, the combination of a plurality of brim clamps comprising complementary gripping members, one of said members having a cam surface thereon, means engaging said cam surface to swing 130

the brim clamps outwardly, and means on said cam surface engaging in said last named means to guide the brim clamps as they are swung outwardly.

5 6. In a hat blocking machine, the combination of a plurality of pivotally mounted brim clamps adapted to grip the edge of a hat therebetween, and having cam surfaces disposed between the fulcrums and gripping 10 portions thereof, and means engaging the cam surfaces to swing the clamps outwardly and to return the brim clamps inwardly to retracted position.

7. In a hat blocking machine, the combination of a plurality of pivotally mounted brim clamps, cam surfaces thereon disposed between the fulcrums and clamping portions thereof, and an expansion ring engaging said cam surfaces to swing the clamps outwardly 20 to stretch a hat brim gripped thereby and to return the brim clamps inwardly to retracted position.

8. In a hat blocking machine, the combination of a plurality of brim clamps, each having an angularly disposed portion and a side- 25 wardly disposed extension thereon, an expansion ring engaging said angularly disposed portions, and an operative connection therebetween and including means on said expansion ring extending thru said extensions whereby actuation of said expansion ring in one direction forces the clamps outwardly and in the reverse direction returns the clamps into retracted position.

30 9. In a hat blocking machine, the combination of a plurality of brim clamps having angularly disposed portions thereon, an expansion ring engaging said portions, an operative connection between the brim clamps and the expansion ring whereby actuation of said expansion ring in one direction swings the clamps outwardly and in the reverse direction returns the clamps into retracted position, said connection comprising a slotted extension 35 on said angularly disposed portions, and pins extending therethru and fixed in said expansion ring.

10. In a hat blocking machine, the combination of a plurality of brim clamps adapted 50 to grip the edge of a hat therebetween, means engaging the brim clamps to swing the clamps outwardly to stretch the hat brim and to return the brim clamps inwardly to retracted position, and means on said brim clamps engaging in said first named means to guide the brim clamps during actuation thereof.

11. In a hat blocking machine, the combination of a plurality of brim clamps, an expansion ring engaging the brim clamps, an operative connection between the brim clamps and the expansion ring whereby actuation of said expansion ring in one direction swings the clamps outwardly and in the reverse direction returns the clamps into retracted position, and means on said brim

clamps engaging in said expansion ring to guide the brim clamps during actuation thereof.

12. In a hat blocking machine, the combination of a plurality of brim clamps, an expansion ring engaging the brim clamps, an operative connection between the brim clamps and the expansion ring whereby actuation of said expansion ring in one direction swings the clamps outwardly and in the reverse direction returns the clamps into retracted position, said connection comprising a slotted extension on said clamps, a pin extending therethru and fixed in said expansion ring, and means on said brim clamps engaging in said expansion ring to guide the brim clamps during actuation thereof. 70 75

13. In a hat blocking machine, the combination of a plurality of brim clamps, an expansion ring engaging the brim clamps, an operative connection between the brim clamps and the expansion ring whereby actuation of said expansion ring in one direction swings the clamps outwardly and in the reverse direction returns the clamps into retracted position, and tongues extending from said brim clamps engaging in grooves in said expansion ring to guide the brim clamps during actuation thereof. 80 85

14. In a hat blocking machine, the combination of a plurality of brim clamps, an expansion ring engaging the brim clamps, an operative connection between the brim clamps and the expansion ring whereby actuation of said expansion ring in one direction swings the clamps outwardly and in the reverse direction returns the clamps into retracted position, said connection comprising a slotted extension on said clamps, a pin extending therethru and fixed in said expansion ring, and tongues extending from said brim clamps engaging in grooves in said expansion ring to guide the brim clamps during actuation thereof. 90 95 100

15. In a hat blocking machine, the combination of pivotally mounted brim clamps having cam surfaces disposed thereon between their fulcrums and clamping portions, means engaging said cam surfaces and adapted to be actuated in one direction to expand said brim clamps, means operatively connecting said first named means and said brim clamps whereby actuation of said first mentioned means in another direction actuates the clamps in a reverse direction, and means to actuate said first named means in either direction. 110 115 120

16. In a hat blocking machine, the combination of brim clamps having cam surfaces thereon, means engaging said cam surfaces and adapted to be actuated in one direction to expand said brim clamps, means operatively connecting said first named means and said brim clamps whereby actuation of said first mentioned means in another direction 125 130

actuates the clamps in a reverse direction, means to actuate said first named means in either direction, and means on the brim clamps engaging in said first named means 5 to guide the brim clamps upon actuation thereof.

17. In a hat blocking machine, the combination of brim clamps comprising complementary gripping members, one of which is reciprocably mounted in the other gripping members, the said other gripping members having cam surfaces formed thereon adjacent the gripping portions thereof, the ends of the reciprocable members being operatively joined to a movable member, means to actuate said movable member to bring said reciprocable members into and out of gripping engagement with said other gripping members, and means engaging said cam surfaces 29 to expand and retract the brim clamps.

18. In a hat blocking machine, the combination of brim clamps comprising complementary gripping members, one of which is reciprocably mounted in the other gripping members, the said other gripping members having cam surfaces formed thereon adjacent the gripping surfaces thereof, the ends of the reciprocable members being operatively joined to a movable member, and means to actuate said movable member to bring said reciprocable members into and out of gripping engagement with said other gripping members, both of said gripping members being mounted for a swinging movement into expanded and retracted positions, and means engaging the cam surfaces on said other gripping member to expand and retract the brim clamps.

19. In a hat blocking machine, the combination of brim clamps in spaced relation and comprising complementary gripping members, one of which is reciprocably mounted in the other, the ends of the reciprocable members being operatively joined to a movable member, means to actuate said movable member to bring said reciprocable members into and out of gripping engagement with said other gripping member, both of said gripping members being mounted for a swinging movement into expanded and retracted positions, reciprocable means engaging said other gripping member to expand and retract the brim clamps, and means operative between said other gripping members and said last named means to guide said brim clamps in their spaced relation during their actuation.

20. In a hat blocking machine, the combination of brim clamps arranged in spaced relation and comprising complementary gripping members, one of which is reciprocably mounted in the other, means to reciprocate said reciprocable members to actuate said members into and out of gripping engagement with said other members, both of said members being mounted for a swinging

movement into expanded and retracted position, said other gripping members having angularly disposed portions thereon, an expansion ring adapted to engage said portions to expand and retract the brim clamps, and 70 an operative connection between said expansion ring and said portions comprising a slotted extension on said portions, and a pin extending therethrough and fixed to the expansion ring. 75

21. In a hat blocking machine, the combination of brim clamps arranged in spaced relation and comprising complementary gripping members, one of which is reciprocably mounted in the other, means to reciprocate said reciprocable members to actuate said members into and out of gripping engagement with said other members, both of said members being mounted for a swinging movement into expanded and retracted position, an expansion ring adapted to engage said other gripping members to expand and retract the brim clamps, an operative connection between said expansion ring and said brim clamps comprising a slotted extension 90 on the brim clamps, a pin extending therethru and fixed to the expansion ring, and tongues on the brim clamps engaging in grooves in said expansion ring whereby said brim clamps are guided during their actuation. 95

22. In a hat blocking machine, the combination of a band selected in accordance with the crown size of the hat to be blocked, means to support said band, means to grip the edge of a hat body positioned in said band, a hat block, means to force said hat block within the band and into the hat body, and means engaging the square portion of the hat crown to remove wrinkles therefrom. 100 105

23. In a hat blocking machine, the combination of a band selected in accordance with the crown size of the hat to be blocked, means to support said band, means to grip the edge of a hat body positioned in said band, a hat block, means to force said hat block within the band and into the hat body, and means engaging the outer crown portion of the hat to remove wrinkles therefrom, said last named means comprising a pad adapted to 110 115 frictionally engage the hat crown.

24. The art of blocking hats which consists in mounting a hat body within a band of dimensions determining the crown size of the finished hat, gripping the hat about its brim edge, stretching the brim substantially throughout its area by pulling out the gripped brim edge in a linear direction and in the general plane of the forming edge of the band, inserting a hat block thru the band, 120 and forcing the block into the crown of the hat body to thereby adapt the crown portion of the hat to the block and pull the hat relatively over the band. 125

25. The method of dry blocking hats which 130

consists in mounting a hat body within a band of dimensions determining the crown size of the finished hat, gripping the hat body throughout its brim edge, directing steam 5 against the hat body, stretching the brim substantially throughout its area by pulling the gripped brim edge in a linear direction and in the general plane of the forming edge of the

band, and forcing a hat block thru the band into the crown of the hat body, to thereby 10 pull the body over the band from its secured brim edge.

Signed at Danbury, Connecticut, this 19th day of October, 1926.

HUGH W. HUNTER.
